COMBINED STROLLER AND HIGH CHAIR

Alvin L. Johnson, Worcester, Mass.

Application July 26, 1951, Serial No. 238,611

8 Claims. (Cl. 155—38)

1

This invention relates to a combined stroller and adjustable chair, such as a child's high chair, and it is an object of the invention to provide a chair structure which can be attached to a wheel chassis to form a stroller, or be detached from the chassis and be used as a chair.

It is a further object of the invention to provide a seat unit slideable vertically on the chair structure and held in adjusted vertical position by lock or holding means on the unit engageable with the chair structure.

It is another object of the invention to provide the seat unit with brake means overhanging the wheels of the chassis and engageable with the wheels when the unit is in low position to enable the seat unit by its weight to prevent turning of the wheels and thus hold the article from rolling away accidentally.

It is a still further object of the invention to provide the chassis with guide bars along which the base of the chair structure can slide into holding engagement with a hook or similar holding element on the chassis, after which a latch or the like can be moved to lock the chair structure to the chassis.

In the accompanying drawings, wherein two forms of the invention are illustrated as examples of means for achieving the foregoing and other objects to be pointed out,

Fig. 1 is a side elevation of the preferred form of the invention showing the chassis attached to the chair structure and the seat unit in two different positions,

Fig. 2 is a rear elevation looking in the direction of arrow 2, Fig. 1,

Fig. 3 is an enlarged detail vertical section on line 3—3, Fig. 2, showing the lower part of the chair structure attached to the chassis in full lines and in detaching position in dotted lines,

Fig. 4 is a detail rear elevation looking in the direction of arrow 4, Fig. 3, showing the latch in two positions,

Fig. 5 is an enlarged detail vertical section on line 5—5, Fig. 2,

Fig. 6 is a vertical section on line 6—6, Fig. 5,

Fig. 7 is an enlarged vertical section on line 7—7, Fig. 1,

Figs. 8 and 9 are detail horizontal sections on lines 8—8 and 9—9, respectively, Fig. 7,

Fig. 10 is an enlarged detail horizontal section on line 10—10, Fig. 2,

Fig. 11 is a detail vertical section on line 11—11, Fig. 10,

Fig. 12 is an enlarged detail horizontal section on line 12—12, Fig. 1,

2

Fig. 13 is a diagrammatic plan view of the chassis on a reduced scale, looking in the direction of arrow 13, Fig. 1,

Fig. 14 is a diagrammatic perspective of the seat supporting structure, the seat unit being removed,

Fig. 15 is a diagrammatic perspective of the seat unit removed from the supporting structure, parts being omitted,

Fig. 16 is a diagrammatic side elevation of the chair supporting structure and seat unit detached from the chassis for use as a chair, and

Fig. 17 is a diagrammatic view similar to Fig. 1 but showing a modified form of the invention.

15 The preferred form of the invention shown in Figs. 1 and 2 comprises a chassis, a chair supporting structure, and a seat unit designated generally at A, B and C, respectively. These parts are shown in Figs. 1 and 2 assembled to form a 20 stroller or go-cart for a young child.

The chassis A has front and back parallel axles 1 and 2, respectively on which are journaled wheels the front pair of which are shown at 3 while the rear pair are shown at 4. Extending 25 backwardly and forwardly of the chassis are side bars 5 and 6 secured to the axles by bolts 7, see Fig. 6. The bars are preferably made of angle iron stock having vertical flanges 8 from the lower ends of which extend horizontal flanges 9.

An attaching member 10 formed preferably of sheet metal is secured to the top of the axles at 11 and extends between the bars 5 and 6. The front end of member 10 is bent upwardly and then backwardly to form a hook 12 opening rearwardly and having the upper end 13 rearward of the front end of member 10 and defining a pocket 14, see Fig. 3.

The rear end of member 10 is bent upwardly to form a wall 15 having a horizontal pivot bolt 16 passing therethrough. A holding means or latch 17 is pivoted on the bolt and has a notch 18 in the left edge thereof as viewed in Fig. 4. The latch is made preferably of flat metal and the lower end 19 thereof serves as a hand hold. Friction washer means 20, Fig. 3, may be used to hold the latch in any position to which it may be used relative to wall 15.

The supporting structure or frame B is made for the most part of light weight but strong preferably metallic tubular material. It includes a tubular U-shaped base or foot 25 having parallel side arms 26 and 27 joined by a cross arm 28, see Fig. 14. The side arms are spaced such that they can rest on the horizontal flanges 9 between the vertical flanges 8 of the chassis, and

the cross bar 28 is of a size to fit snugly into pocket 14. The hook 12 and cross bar 28 form separable pivotal elements which cooperate to connect the forward parts of the chassis and base.

As shown herein an angle element 30 fits into the rear end of each side arm 26 and 27 and is secured in place, as by welding or fusing. Each element 30 has an upright rear end 31 and these ends are secured to a cross member 32 conveniently made of angle iron with a vertical rear wall 33 and a horizontal flange 34. The ends of wall 33 extend beyond the flange 34 and are secured, as by welding, to the rear sides of the upright ends 31 of the elements 30. A latch bolt 17 or the like 35 is secured to and extends rearwardly from wall 33 for cooperation with the latch 17 of the chassis.

The upper part of the structure B is made preferably of a single piece of tubular stock having uprights 40 and 41 which are parallel and have their lower ends fitted into and secured as by welding to the upright ends 31 of elements 30. The upper part of frame B, designated generally at 42, is thus rigidly secured to the base 25. The uprights may be bent rearwardly as at 43 and joined by a cross handle 44.

Those sides of the uprights which face each other are provided with holes. These holes are arranged in pairs, one hole for each pair in each upright, and the holes of each pair are at substantially the same elevation, see Fig. 7.

The seat unit C is formed with two tubular U-shaped side members 50 and 51, respectively, Fig. 15, each having top and bottom rails 52 and 53, respectively. The rear end of each bottom rail 53 is secured to a fitting 55 having a vertical bore 56 fitting around the corresponding upright 40-41 and having a lateral hole 57 to register with the holes 45.

A vertical adjusting member 60 has a rear wall 61 the ends of which are secured at 62 to the fittings 55. A horizontal flange 63 extends forwardly from wall 61 and has secured thereto two depending guide brackets 64 and 65 each having a locking or holding bolt 66 slidable horizontally therein, see Fig. 7. Each bolt is surrounded by a compression spring 67 acting to urge the associated bolt in one or another of the holes 45 in the corresponding upright 40-41.

A pivot, such as bolt 70, depends from flange 63 and has a lever 71 pivoted thereon. A handle 72 on the lever extends rearwardly to permit manipulation of the lever. The plungers are connected to lever 71 by connectors 73 which are attached to the lever on opposite sides of its pivot, see Fig. 9. By swinging lever 71 from the full line to the dotted line position, Fig. 9, the bolts 66 can be withdrawn from their holes 45.

The rear ends of the upper rails 52 have fittings 75 which are freely slidable on the uprights 40-41 and are similar to fittings 55. When lever 71 is in the dotted line position shown in Fig. 9, therefore, the side members 50 and 51 can slide vertically on the uprights 40-41.

A seat 76 is secured at 77 to the bottom rails 53, and a back 78 has the upper part thereof secured at 79 to the top rails 52. The bottom of the back is supported by a tube 80 which is secured by bolts 81 (one of which is shown in Figs. 10 and 11) to the bottom rails 53. The tube, or cross bar, 80 has its ends extended over the rear pair of wheels 4, and each extended end is fitted with a brake means 85, which may be in the form of a soft rubber thimble held frictionally

on the cross bar 80 and positioned to rest on top of the rim of the wheel under it when the seat unit is in the low position shown in dotted lines, Fig. 2, to prevent turning of the wheel. The wheels extend sufficiently above the base 25 of the frame 42 to permit the brakes to engage the rear wheels.

A foot rest 90 has side arms 91 and 92 secured at 93 to the upright parts 94 of the side frames 50 and 51, and a step 95 is secured to the lower ends of the arms 91 and 92, see Figs. 1 and 16.

When the parts A, B and C are assembled as a stroller a hand rail or guard 100 may be provided as an attachment for the seat unit. As shown in Figs. 1 and 2, and more particularly in Fig. 12 which shows one end of the guard, a rail 101 has each end thereof welded or otherwise secured to an arm 102 having secured thereto a small casing 103 in which is slidable a spring plunger 104 having a grip 105 on its outer end. The plunger fits into a hole 106 in the adjacent upper rail 52, and the rear end of the arm 102 is slotted at 107 to fit a stud or screw 108 on the rail 52. The guard is thus easily attached to the seat unit. When structures B and C are used as a chair, see Fig. 16, an attachment 110 may be used which is similar to attachment 100 except that a tray 111 is used instead of rail 101.

When the three structures A, B and C are used as a stroller the front part 28 of the base 25 will be fitted into pocket 14 and bolt 35 will be in notch 18 of latch 17, and the sides 26 and 27 will be supported and positioned by the bars 5 and 6. When it is desired to use parts B and C as a chair the latch 17 will be moved to the dotted line position of Fig. 4 and the frame B then swung to the dotted line position, Fig. 3, after which the base 25 can be slid rearwardly on the bars 5 and 6 and the attaching member 19 and the frame removed from the chassis. The base 25 can then rest on a floor, see Fig. 16, and structures B and C, with attachment 110 preferably connected to the seat unit, can be used as a child's high chair. Whether used as a stroller or a chair the seat unit C will be vertically adjustable along the uprights 40 and 41.

When the seat unit is in the down or braking position shown in Fig. 2 the plungers 66 will be below the lowest pair of holes 45 and will be urged against the unperforated parts of the uprights 40-41 and the user can grasp the brake parts 85 and lift the seat unit without being required to operate the lever 70.

In the modified form of the invention shown in Fig. 17 the seat unit will be as already described, but the supporting structure or frame 115 will have axles 116 secured directly to a horizontal base 117 at the lower end of the frame 115. In this form the wheels 118 will be permanently connected to the frame and there will be no part corresponding to a removable chassis. The frame 115 has uprights 119 similar to uprights 40-41 in that they can support the seat unit C in various vertical positions, as in the preferred form. The braking feature is the same in both forms.

From the foregoing it will be seen that the invention sets forth an article which in the preferred form comprises a chassis A, a supporting structure or frame B, and a seat unit C which can be assembled to provide a stroller, or the chassis can be removed and parts B and C used as a chair. In both forms of the invention the seat unit is adjustable on uprights and the seat unit 76 when in lowest position where the plungers 66

cannot enter holes 45 the brake elements 85 rest on the rear wheels and the weight of the seat unit is able to hold the wheels from turning. The base 25 and the frame 42 are made of tubular stock joined by the angle parts 30, but the latter are not essential in all forms of the invention but are convenient for joining the parts 25 and 42. Further, the invention is not limited to the type of attaching means, such as latch 17, and it will be sufficient if any suitable means is employed to hold the part B detachably to the part A.

Having now particularly described and ascertained the nature of the invention and in what manner the same is to be performed, what is claimed is:

1. In a combined stroller and chair, a chassis comprising axles, mounting wheels and bars secured to and holding the axles parallel, a supporting structure having a base and parallel upright members fixed with respect to said base, detachable means normally holding the base on said chassis with the members extending upwardly from the base and chassis, said detachable means comprising a hook element at the forward end of the chassis under which part of the base extends and a latch normally operatively connecting the rear parts of the chassis and base movable to a position to disconnect the base from the chassis, and a seat unit supported by said members over the base and chassis, the chassis when attached to said structure forming a stroller therewith and the structure when detached from the chassis being capable of resting on said base to provide a chair.

2. The structure set forth in claim 1 wherein said bars are parallel angle irons each having a vertical and a horizontal flange and said base rests on the horizontal flanges and is swingable upwardly between the vertical flanges around said hook element as a pivot when the latch is in position to disconnect the base from the chassis.

3. The structure set forth in claim 1 wherein said base is slidable rearwardly on said bars to disconnect the forward part of said base from said hook element.

4. The structure set forth in claim 1, wherein said axles are located one at the front of and the other at the rear of said chassis and said hook element is supported by said one axle and the latch is supported by said other axle.

5. In a stroller, a supporting structure having upright parallel members, a base extending forwardly from the lower ends of said members, axles attached to said base, wheels on said axles extending above said base, a seat unit mounted on the members for vertical sliding movement thereon, holding means on the unit to support the latter on said members at a plurality of levels above said base but releasable to permit the unit to slide downwardly on said members, and brake means on the unit overhanging certain of said

wheels normally out of engagement with the latter when said holding means holds the unit in the lowest of said levels, the seat unit when sliding downwardly on said members moving said brake means down against said certain wheels so that the weight of said unit causes said brake means to resist turning of said certain wheels.

6. In a stroller, a supporting structure having upright parallel members, wheels rotatably mounted with respect to and supporting said supporting structure, a seat unit slideable vertically on said members, brake means on said unit overhanging certain of said wheels, and holding means to support the unit on said members with the brake means above and out of engagement with said certain wheels but releasable to permit said unit to slide down by gravity on said members to effect engagement of the brake means with said certain wheels to resist turning of the latter.

7. The stroller set forth in claim 6 wherein said brake means extends beyond said certain wheels relative to said seat unit to afford hand holds by which the unit can be slid upwardly along said members.

8. In a combined stroller and chair, a chassis comprising axles, mounting wheels and bars secured to and holding the axles parallel, a supporting structure having a base and parallel upright members fixed with respect to the base, separable pivotal elements, one on the chassis and the other on the base, capable of cooperation to pivotally connect the chassis and base, latch means movable to one position to connect and to another position to disconnect the chassis and base, and a seat unit supported by said members over the chassis and base, said elements and latch means when in said one position cooperating to fasten the chassis to the base to form a stroller, and the latch when in said other position enabling the base to swing upwardly relatively to the chassis and then in a direction to separate said elements to permit removal of the structure so that the latter can rest on said base to serve as a chair.

ALVIN L. JOHNSON.
